UNITED STATES PATENT OFFICE.

JAMES H. WHITEHOUSE, OF BROOKLYN, NEW YORK, ASSIGNOR TO THE
COLONIAL DAMES OF AMERICA, OF NEW YORK.

DESIGN FOR A BADGE.

SPECIFICATION forming part of Design No. 20,950, dated July 21, 1891.

Application filed June 25, 1891. Serial No. 397,530. Term of patent 14 years.

To all whom it may concern:

Be it known that I, JAMES H. WHITEHOUSE, a subject of the Queen of Great Britain, residing in the city of Brooklyn, county of Kings, 5 and State of New York, have invented and produced a new and original Design for Badges, Insignia, &c., of which the following is a specification, reference being had to the accompanying drawing, forming a part of the 10 same.

My design consists of a full-length standing female figure in the costume of colonial times, with outstretched hand of welcome. Surrounding the figure is a strap or garter 15 which confines a scroll at the lower part of the figure, which scroll may, like the garter,

bear any desired legend. Springing from behind the figure and apparently from underneath the strap or garter is a circlet of rays of light spreading radially outward to a scalloped edge or outline. The whole is to be suspended by a ribbon or otherwise from a bar, which may bear any desired legend. 20

What I claim, and desire to secure by Letters Patent, is—

The design for badges, insignia, &c., consisting of the design substantially as shown. 25

JAMES H. WHITEHOUSE.
